UNITED STATES PATENT OFFICE.

WILLIAM PHILLIPS, OF ROCHESTER, NEW YORK.

LENS-BLANK SETTER FOR LENS-GRINDING MACHINES.

1,332,681.

Specification of Letters Patent.

Patented Mar. 2, 1920.

Application filed June 25, 1917. Serial No. 176,736.

To all whom it may concern:

Be it known that I, WILLIAM PHILLIPS, a citizen of the United States, and resident of Rochester, in the county of Monroe and 5 State of New York, have invented certain new and useful Improvements in Lens-Blank Setters for Lens-Grinding Machines, of which the following is a specification.

The present invention relates to lens blank 10 setters for lens grinding machines, and an object thereof is to provide for securing greater accuracy in the setting of the lens blanks of multifocal lenses in their holders for grinding the short focus curves. Another 15 object of the invention is to provide a construction which can set a plurality of lens blanks on a lens grinder holder so that a curve at any desired angle may be ground, notwithstanding variations in the thicknesses 20 and shapes of the lens blanks. Still another object of the invention is to make provision whereby the axes of short focal curves to be formed in the lens blanks may be positioned at any desired points on the 25 blanks while permitting said points to be relatively the same on all the lenses.

To these and other ends the invention consists of certain parts and combinations of parts, all of which will be hereinafter described, the novel features being pointed out in the appended claims.

In the drawings:—

Figure 1 is a plan view of an embodiment of the invention; 35 Fig. 2 is a vertical section through the construction shown in Fig. 1, with the parts adjusted for grinding concave lenses;

Fig. 3 is a side view of the same embodiment with the parts adjusted for grinding 40 plane lenses;

Fig. 4 is a side view with the parts adjusted for grinding convex lenses;

Fig. 5 is a section on the line 5—5, Fig. 2 and

Fig. 6 is a fragmentary view of the bottom of the setter.

In forming the short focus curves of bifocal or multifocal lenses it is customary to set a plurality of lens blanks in pitch 50 upon a lens holder by means of a setter which conforms substantially to the curve to be ground on the lenses. With this method a separate setter must be provided for each curve and no provision is made 55 whereby the distances between the lenses may be uniform. Not only is a great ex-

pense necessary to provide a number of setters corresponding to the various curves to be formed, but it is impossible to grind any two lenses alike, that is, to have the curves 60 for the second focal points arranged with their axes positioned at the same distance on each of the lenses. As a consequence a great deal of waste is caused because two bifocal lenses must have their short focal axes 65 positioned alike with reference to the edges of their respective lenses.

To overcome the above objections it has been suggested to mount the lens blanks upon a holder provided with rigid abutments which define the positions of the lens blanks on the holder, and then to surround the lens blanks with pitch or resin. See, for example, U. S. Patent #937,763, granted October 26, 1909 to F. Buchhop. Provision 70 was also made in such holder for the adjustment of the rigid abutments to obtain different angles for grinding different curves. But this construction is defective in three respects: First, it did not take into consider- 75 ation that lens blanks are of different thicknesses and that when holding at one time a number of lenses of different thicknesses the curves formed for the short focus would be of different depths; secondly, it failed to 80 make provision for obtaining on the same machine, any positioning of the axis of the short focal curve with reference to the edge of the lens; and third, no provision was made for grinding the curves at any angle 85 on a concave lens blank, a flat lens, or a convex lens blank.

According to this invention it is possible to position lenses on a lens holder employing pitch or resin so that the thicknesses of the 90 lens blanks need not be taken into consideration while, at the same time, the axes of the short focal curves may be situated at any points with reference to the edges of the blanks and this so that these points will be 95 the same on any desired number of lenses. Furthermore, one setter may be employed for positioning blanks to form curves at 100 any angles.

Referring more particularly to the drawings where one embodiment of the invention is illustrated, 1 indicates the supports for the lens blanks, these supports preferably having a face 2 shaped to conform to that face of the lens blank on which the short 105 focal curve is to be ground. In this instance the face 2 is concave so as to conform

to the convex face of a lens blank. Each support is also provided preferably with retaining devices 3 which will properly position the blank on the support but will readily permit such blank to be withdrawn by the pitch or resin of the holder of the grinding machine. In this instance these retainers are in the form of four spring fingers arranged symmetrically about each support. 5 In this embodiment of the invention the blank supports are symmetrically arranged about a common center and are each pivotally mounted adjacent 4 at their proximate sides. 10 Preferably the lens blank supports are moved equal distances simultaneously about their axes 4 and to this end each support 1 has a link 5 pivoted thereto at 6 near its outer edge, said links 5 being pivotally connected at 7 to a common collar or ring 8 mounted to turn on a tubular base member 9. In this base member 9 a supporting member 10 is guided, the supporting member carrying the blank supports 1. Mounted 15 to turn in the base member 9 is a screw 11 having a hand wheel 12 and engaging the supporting member 10 to move the latter on the base member. It is apparent that the relative movement of the supporting member 10 and the base member 9 will, through the links 5, cause the blank supports 1 to turn simultaneously on their pivots 4, thus permitting said blank supports to be swung to a common plane, as shown in Fig. 3, or to 20 assume any desired angle on either side of said plane. 25 To the end that the centers of the short focal curves may be situated at any desired points on the lens blanks, the blank supports 0 are relatively adjustable, this adjustment preferably taking place simultaneously in all of the holders at an equal amount and being preferably in directions radial to a common point centrally of the blank holders. 40 In this instance, this adjustment is secured by mounting each pivot 4 on a block 13 which is guided radially on a rotary carrier 14 mounted to turn on the supporting member 10, the latter being provided with 45 a volute rib 15 which is engaged by projections 16 on the under sides of each block 13 so that on the rotation of the carrier 14, the blocks 13 will be adjusted radially of the carrier and shift the pivots 4 toward and 50 from the center of rotation of the carrier. In this way the lens blanks may be positioned by the setter at any desired distance from the center of the holder of the grinding machine, in order that the optical axis 55 of the short focal curve will be located at the proper distance from the edge of its lens. 60 With the purpose in view of indicating the angle at which the blank supports are set, the supporting member 10 is provided 65 with a scale 17 with which cooperates the

upper end 18 of the base 9 to act as a pointer. Such divisions of this scale may be obtained from a fine adjustment indicator comprising a pointer 19 on the screw 11 coöperating with a dial plate 20 surrounding the screw 70 and also acting to hold the latter to the base member.

To the end of preventing the pitch or resin being trapped at the center of the setter, a filler 21 may be positioned between the lens 75 blank holders to close the space at this point.

In using the invention blank holders 1 are provided each with a face conforming to the faces of the lens blanks to be ground. If the blank face is concave, the holder will have a 80 convex face, if the blank face is a plane, the holder will have a plane face, and if the lens blank is convex, the holder will have a concave face, as illustrated in the present embodiment. The holders are first adjusted 85 radially by means of the rotary carrier 14 which when turned shifts the blocks 13 on which the pivots 4 of the blank holders are mounted. This adjustment is provided in order that the optical axes of the short focal 90 curves may be positioned properly with reference to the edges of the lenses. After this adjustment is secured, the hand wheel 12 is turned until the upper portion of the base member 6 coöperates with the desired division 95 on the scale 17. Should a finer adjustment be desired than is provided for in the scale 17, this is attained by means of the finger 19 coöperating with the dial plate 20. It is apparent that the lens blank holder 1 100 may be adjusted to a common plane, as shown in Fig. 3, or to lie at different angles on opposite sides of the plane, as shown in Figs. 2 and 4. After the setter has been 105 adjusted and the blanks have been applied thereto, the setter is used to apply the blanks to the holder of the grinding machine which, as usual, is provided with pitch or resin in which the blanks are embedded. Owing to the fact that the blanks have their faces on 110 which the short focal curves are to be ground coöperating with the setter, the thickness of the lens is immaterial, as a thick lens will be embedded in the pitch or resin at a greater depth than a thin lens, and all the 115 faces of all the lenses to be ground will lie the same distance from the holder of the grinding machine. By this arrangement it is possible to grind a number of lenses all having the same curve with the optical axis 120 of said curve situated at the same distance from the edge of the lens.

What I claim as my invention and desire to secure by Letters Patent is:—

1. A setter for applying lens blanks to 125 the holders of grinding machines comprising a main support, a plurality of blank supports, each blank support having means for positioning a blank thereon, said means being constructed to release the blank when 130

- the latter is applied to the lens holder of the grinding machine, and means for supporting the blank supports on the main support to permit such blank supports to assume different angles with reference to a common plane.
2. A setter for applying lens blanks to the holders of lens grinding machines comprising a main support, a plurality of blank supports, means supporting the blank supports on the main support so that the blank supports may assume different angles with reference to a common plane, and means for simultaneously moving said supports through equal distances to cause the support to assume any desired angle on either side of a common plane.
3. A setter for applying lens blanks to the holders of lens grinding machines comprising a main support, a plurality of lens blank supports, and means for supporting said lens blank supports on the main support to permit said lens blank supports to be adjusted toward and from a common center and also with reference to a common plane.
4. A setter for applying lens blanks to the holders of lens grinding machines comprising a main support, blocks movable on the main support relatively to each other toward and from a common center, and lens blank holders pivotally mounted on said blocks.
5. A structure as set forth in claim 4, combined with means for simultaneously moving the blocks toward and from a common center.
6. A structure as set forth in claim 4, combined with means for simultaneously moving the lens blank holders on their pivots to cause them to assume any desired angle with reference to a common plane.
7. A structure as set forth in claim 4, combined with means for simultaneously moving the blocks toward and from a common center, and means for simultaneously moving the lens blank holders on their pivots to cause them to assume any desired angle with reference to a common plane.
8. A setter for applying lens blanks to the holders, of lens grinding machines, comprising a main support, a plurality of lens blank holders having relative movement on said main support, and each having a face conforming to the lens blank face on which the curve is to be ground.

WILLIAM PHILLIPS.
